UNITED STATES PATENT OFFICE.

CHARLES EDWARD HAVILAND, OF LIMOGES, FRANCE.

DESIGN FOR A DISH.

SPECIFICATION forming part of Design No. 20,633, dated March 24, 1891.

Application filed December 26, 1889. Serial No. 335,030. Term of patent 14 years. Patented in France July 11, 1889, No. 270.

To all whom it may concern:

Be it known that I, CHARLES EDWARD HAVILAND, a citizen of the United States, residing at Limoges, in the Republic of France, have 30
5 invented and produced a certain new and original Design for Dishes of a Table-Service, fully described and represented in the following specification and the accompanying drawings, forming a part of the same, the said improvements having been patented in France July 11, 1889, under the number 270.

The distinguishing characteristics of this design consist in the shape of the dish and the shape and edge ornamentation of its cover, 35 15 as illustrated in the accompanying illustrations, in which—

20 Referring to said figures, it will be seen that the dish therein illustrated is substantially elliptical in horizontal section. It is provided at each end and upon opposite sides of its longer axis with a recess 1. The dish may 40
25 also be provided with a slight inward bend 2, and the recesses 1 may be spanned by handles 3 of any desired form. The cover 4 of the dish has a contour corresponding, when viewed horizontally, with the contour of the dish. The side sections 5 of the cover are each provided with an edge border 6 in bas-relief, formed of irregular curves and terminating in scrolls 7 8. The end sections 9 are provided with an irregularly fluted or wrinkled edge 10. 35

What I claim is—

1. The design for a dish, substantially as shown and described.
2. The design for the cover of a dish, substantially as shown and described.
3. The design for a dish and its cover, substantially as shown and described.

In testimony whereof I have hereunto set my hand in the presence of two subscribing witnesses.

CHARLES EDWARD HAVILAND.

Witnesses:

ALBERT HAVILAND,
GASTON LONGEVIALE.
